York

Filed May 31, 1962, Ser. No. 70,362

Term of patent 14 years

(Cl. D36—8)

FIG. 1 is a side elevational view of a champagne goblet embodying my new design.

FIG. 2 is a sectional elevation of the same.

The bowl, stem and base are round when viewed in plan.

I claim:

The ornamental design for a champagne goblet or the like, as shown and described.
